ADJUSTABLE WRENCH

Original Filed August 12, 1922

FIG. 1.

FIG. 2.

FIG. 5.

FIG. 4.

FIG. 6.

INVENTOR:

JOHN V. LARSON,

BY Robert Burns, Atty.

UNITED STATES PATENT OFFICE.

JOHN V. LARSON, OF CHICAGO, ILLINOIS.

ADJUSTABLE WRENCH.

Application filed August 12, 1922, Serial No. 581,344. Renewed March 16, 1926.

This invention relates to that type of adjustable wrenches in which the movable jaw member and its operating sleeve nut are connected to the companion stationary jaw member by an intermediate rocker yoke pivotally mounted on the stationary jaw member, to permit of limited independent movement between the jaw members in attaining the proper initial holding grip upon the article operated on, and the present improvement has for its various objects:—

To provide a structural formation of the rocker yoke adapting the same for effective engagement with the operating sleeve nut and with the stationary jaw member, in an economical and durable manner, and with which accidental turning of the operating sleeve nut, by contact with exterior surfaces or objects is prevented.

To provide a simple, economical and durable formation of the guide housing, by which the parts are enclosed and guided after assembly and in actual use, all as will hereinafter more fully appear.

In the accompanying drawing:

Fig. 1 is a side elevation of an adjustable pipe wrench, embodying the present improvements;

Fig. 2 is a transverse section on line 2—2, Fig. 1;

Fig. 3 is a detail longitudinal section on line 3—3, Fig. 2;

Fig. 4 is a detached perspective view of the plate metal guide housing;

Fig. 5 is a similar view of the rocker yoke member; and

Fig. 6 is a view of the plate metal blank or stamping from which the yoke member is shaped.

Like reference numerals indicate like parts in the several views.

In the drawings, 1 designates a guide housing formed of plate metal and having a flat U-shape in cross-section with the side walls or plates in spaced parallel relation, united together at top by a cross web as shown.

2 designates openings formed in the side walls or plates of the housing in transversely aligned relation, and each formed with a rounded bearing recess or socket 3 at its lower and forward corner, and with a curved

bearing surface 4 at its rear end as shown and for the purpose hereinafter stated.

The formation of the guide housing 1 of 55 plate metal is in itself old and in general use, and no claim per se is made thereto other than the detail formations and features thereof and by which coaction is attained with the associated parts of the mechanism. 60

5 designates the operating handle or lever fixedly secured at its forward end between the lower portions of the side walls or plates of the housing 1 by rivets or other fastening means, and formed at its forward and upper 65 corner with an upturned hook shape abutment lug 6, acting as a part of the pivot rest for the rocker yoke hereinafter described. In the construction shown, the handle or lever 5, is provided with side lugs 7 constituting bearing abutments for the rear ends of the housing 1, to aid in strengthening the connection of the parts.

8 designates the stationary jaw of the wrench, secured between the forward and 75 lower ends of the side walls or plates of the housing 1 by a rearwardly extending rib or fin abutting against the forward end of the handle 5, as shown in Fig. 1.

9 designates the forwardly arranged adjustable jaw of the wrench, formed with a rearwardly extending screw threaded shank 10, in angular relation to said jaw portion, and having the usual rectangular or other non-circular form in cross-section adapting 85 the same for sliding movement between the side walls or plates of the housing 1 and in a plane above the lever or handle 5 aforesaid.

11 designates an adjusting sleeve nut 90 formed for manual rotation and arranged within the aforesaid openings 2 of the side walls of the housing 1, with its screw-threaded bore in operative engagement with the screw-threads of the shank 10 aforesaid. 95

12 designates a rocker yoke, which in the present improvement is formed from a plate metal blank of the required form and so bent and shaped as to provide a main portion 13 of a disk shape having a central 100 orifice adapted to fit over the movable jaw shank 10, and a forwardly extending guide tongue 14, adapted for guiding movement between the side wall of the housing 1. Also

to provide a forwardly extending pivot prong 15 at the lower and forward corner of the rocker yoke, and produced by a return bend of the metal of the blank, said pivot 5 prong 15 being adapted for pivotal bearing in the bearing recesses 3, of the housing 1 and in the abutment recess of the lug 6, of the handle 5. Also to provide a rearward extension 16 in right-angle relation to the 10 main disk portion 13, with said extension 16, having at its rear end an angular lug 17 arranged in the path of the sleeve nut 11 aforesaid, to limit independent rearward movement of the sleeve nut with relation to the 15 rocker yoke, and in addition to have sliding engagement against the curved bearing surfaces 4, of the housing 1, above described, to prevent independent rearward movement of rocker yoke with relation to 20 the housing 1.

In the present construction, the orificed disk portion 13, aforesaid, is arranged in front of the operating sleeve nut 11, and is adapted to limit independent forward movement of said sleeve nut with relation to the 25 rocker yoke 12. In the preferred construction shown, said orificed disk portion 13, has a diameter greater than the sleeve nut 11 for the purpose of guarding said nut 30 from contact with exterior objects and prevent accidental turning of the nut thereby.

18 designates a spring interposed between the rocker yoke 12, and the handle or lever 5, and adapted to yieldingly swing the yoke 35 12, sleeve nut 11, and the shank 10, of the movable wrench jaw 9, in a direction away from the handle 5, and normally hold the movable wrench jaw 9, in a position nearer the fixed wrench jaw 8, in order to require 40 a pressure of the thumb of the operator upon the rear portion of the shank 10, to attain an initial and limited opening of the jaws in applying the wrench to a pipe or the like. Said spring feature and its 45 function is common in the present type of adjustable pipe wrenches.

Having fully described my invention which I claim as new and desire to secure by Letters Patent, is:—

50 1. In an adjustable wrench of the type described, the combination of a fixed jaw member having an operating handle, a plate metal housing of a flat U-shape fixedly secured to the forward end of said handle 55 with its parallel side walls formed with transversely aligned openings which in turn are formed with pivot recesses at their lower front corners and with curved bearing surfaces at their rear ends, a movable jaw member having a screw-threaded shank sliding 60 in said housing, a sleeve nut arranged in said openings and having operative engagement with said shank, and a rocker yoke of an angular form pivoted in the aforesaid 65 pivot recesses of the housing and having

sliding engagement at its rear end with the curved surfaces in the openings of the housing, said rocker yoke having bearing engagement with said sleeve nut.

2. In an adjustable wrench of the type 70 described, the combination of a fixed jaw member having an operating handle, a plate metal housing of a flat U-shape fixedly secured to the forward end of said handle with its parallel side walls formed with 75 transversely aligned openings which in turn are formed with pivot recesses at their lower front corners and with curved bearing surfaces at their rear ends, a movable jaw member having a screw-threaded shank sliding 80 in said housing, a sleeve nut arranged in said openings and having operative engagement with said shank, and a rocker yoke formed of plate metal and comprising an orificed disk portion encircling the shank 85 aforesaid and provided at its lower end with a forwardly extending pivot lug fitting the pivot recesses of the housing and near its upper end with a forwardly extending guide tongue adapted for sliding movement between the side walls of the housing, said disk portion having bearing engagement with the sleeve nut.

3. In an adjustable wrench of the type 90 described, the combination of a fixed jaw member having an operating handle, a plate metal housing of a flat U-shape fixedly secured to the forward end of said handle with its parallel side walls formed with transversely aligned openings which in turn are formed with pivot recesses at their lower and front corners and with curved bearing surfaces at their rear ends, a movable jaw member having a screw-threaded shank sliding 100 in said housing, a sleeve nut arranged in said openings and having operative engagement with said shank, and a rocker yoke formed of plate metal and comprising an orificed disk portion encircling the shank 105 aforesaid and a lower rearward extension 110 adapted for sliding engagement with rear curved surfaces of the openings of the housing, said rocker yoke having at its lower forward corner a forwardly extending pivot lug fitting the pivot recesses of the housing 115 and formed by a rebend of the metal, said disk portion having bearing engagement with said sleeve nut.

4. In an adjustable wrench of the type 120 described, the combination of a fixed jaw member having an operating handle, a plate metal housing of a flat U-shape fixedly secured to the forward end of said handle with its parallel side walls formed with transversely aligned openings which in turn are formed with pivot recesses at their lower front corners and with curved bearing surfaces at their rear ends, a movable jaw member having a screw-threaded shank sliding 125 in said housing, a sleeve nut arranged 130

in said openings and having operative engagement with said shank, and a rocker yoke formed of plate metal and comprising an orificed disk portion encircling the shank aforesaid and a lower rearward extension having an upturned flange at its rear end adapted for sliding engagement with rear curved surfaces of the openings of the hous-

ing, said rocker yoke having at its lower forward corner a forwardly extending pivot lug fitting the pivot recesses of the housing, said disk portion having bearing engagement with said sleeve nut.

Signed at Chicago, Illinois, this 7th day of August, 1922.

JOHN V. LARSON.
